CANDY PREFORMING MACHINE

Leo Latini, Chicago, Ill.

Application November 27, 1942, Serial No. 467,091

13 Claims. (Cl. 107—8)

1

This invention relates to candy making machines and more particularly to candy preforming devices for producing hard candies in conjunction with a stick, such as confections commonly termed suckers, although certain features thereof may be employed with equal advantage for other purposes.

It contemplates more especially the provision of an improved, more simple and highly efficient hard candy preforming machine, preferable though not essentially for producing candies having attached sticks associated therewith during the formation thereof.

Numerous types of candy preforming machines have heretofore been proposed, including machines for the production of candy consumed with the aid of a stick, such as suckers, but these are intricate, expensive and massive machines that entail a substantial financial investment and require a great deal of floor space. So that hard candy producing machines of a sucker type may be rendered available to the average manufacturer whose volume does not warrant the use of intricate, expensive and large, cumbersome equipment, novel means have been provided to produce preformed hard candies of a sucker type in large quantities without requiring expensive and intricate equipment.

One object of the present invention is to simplify the construction and to improve the operation of devices of the character mentioned.

Another object is to provide improved candy preforming machines for producing hard candies of a sucker type with simple, compact and highly efficient instrumentalities.

Still another object is to provide a machine of a rotary table type with a plurality of complementary die members that are cooperatively actuated in timed relation to feed, preform, effect the association of a stick therewith and accomplish the ejection thereof for discharge in a continuity of high speed operations.

A further object is to provide hard candy preforming devices including complementary die elements that are actuated in timed relation to form hard candy confections in conjunction with a stick serving as a handling expedient therefor.

A still further object is to provide preforming die elements that are movable relative to each other for actuation by stationary cam tracks responsive to the rotation of a table mount therefor.

Still a further object is to provide candy and stick feeding instrumentalities in conjunction with complementary die elements that are movable

relative to each other in timed relation responsive to the rotation of a table mount in the path of stationary cam tracks.

Other objects and advantages will appear from the following description of an illustrated embodiment of the present invention.

In the drawings:

Figure 1 is a side view in elevation of the device embodying features of the present invention, parts thereof being broken away and shown in section to clarify the illustration.

Figure 2 is a fragmentary perspective view of preformed plastic candy in cylindrical ribbons substantially fed to the feeding rollers of the machine shown in Figure 1.

Figure 3 is a perspective view of a unit or segment severed from the ribbon shown in Figure 2 for introduction into the complementary dies for preforming in accordance with the teachings of the present invention.

Figure 25 is a perspective view of the lower cam track for actuating the lower die complement.

The structure selected for illustration is not intended to serve as a limitation upon the scope or teachings of the invention, but is merely illustrative thereof. There may be considerable variations and adaptations of all or part of the teachings depending upon the dictates of commercial practice. The present embodiment comprises a frame 10 having a frame top 11 supported by a plurality of corner legs or standards 12 to elevate the frame top 11 from the supporting floor so that a continuous strand or ribbon of plastic candy can be fed thereto, as will appear more fully hereinafter. A bottom plate 13 extends between the corner legs or standards 12 for the attachment to lugs 14 formed integral with the lower end regions of the standards 12. To this end, the bottom plate 13 is supported and attached to the lugs 14 by means of suitable fasteners such as bolts 15. The bottom plate 13 serves to rigidify the corner legs or standards 12, as well as supports operating instrumentalities to be hereinafter described.

An attendant guides the strand or ribbon of plastic candy to a substantially U-shaped guide bracket 16 that is supported by a bracket 17 fixed to the frame top 11 near one side 18 thereof. Confronting feed rollers 19 and 20, in this instance too, are vertically journaled in the stub shafts 21 and 22, respectively, so that the substantially semi-circular grooved peripheries 23 of the rollers 19—20 will be in confronting edge contact as at 24 (Figure 4), to define the enclosed circular passage 25 conforming substantially with the shape of the strand or ribbon of plastic candy that is manually or automatically fed thereto.

The stub shafts 21—22 terminate in threaded fastener nuts 26 to retain the feed rollers 19—20 on the stub shafts 21—22 and against supporting shoulders 27—28 comprising a part of comparatively larger gear driven shafts 29—30. The gear driven shafts 29—30 extend downwardly for journalled support in vertically spaced bearings 31—32 and 33—34 that are press fitted into vertical tubular bearing brackets 35 and 36, respec-

tively. The tubular bearing brackets 35—36 have enlarged base flanges 37, which afford their attachment to a somewhat upraised portion 38 of the frame top 11. It should be noted that the feed rollers 19—20 extend inwardly through openings 39—40 (Figure 5) provided in the upstanding sides of the guide brackets 16, so that the confronting peripheral edges 24, defined by a substantially circular passage 25 therebetween, will provide a frictional grasp upon the candy strand or ribbon 41 (Figure 2) for its intermittent feeding towards die members, which will be described hereinafter.

In order to sever the continuous strand or ribbon of plastic candy 41 into segments 42 for deposit into complementary die members, a vertically reciprocal knife 43 is attached to a cross bar 44 by means of fasteners such as machine screws 45 (Figure 14), for vertical reciprocation in the path of the plastic candy strand or ribbon 41, that is moved over a predetermined path by the intermittently rotating feed rollers 19—20. It should be noted that the cross bar 44, provided with vertical bores 46 in the ends thereof to receive bearings 47, are press fitted therein to slide over vertical guide posts 48. The vertical guide posts 48 terminate in threaded lower extremities 49 of reduced diameter, which project in somewhat larger apertures provided in the frame top 11, which serves as a rigid support by means of correspondingly threaded nuts 51, engaging the lower projecting extremities of the threaded nuts 49. The guide posts 48 are spaced beyond the feed guide bracket 16 proximate to the inward extremity thereof to guide the vertical movement of the knife 43 against the extreme inward edge 52 (Figure 6) that cooperates therewith to sever the strand 41 into segments or units 42 (Figure 3).

The cross bar 44 has a pair of spaced depending webs 53 and 54 formed integral therewith to cooperate with furcated links 55—56 that are pivotally connected therewith through connecting pintles 57—58. The furcated links 55—56 have rods 59—60 threaded thereto as at 61 to project outwardly through enlarged openings 62—63 provided in the frame top 11 to constitute actuating instrumentalities connected with the source of power as will appear more fully hereinafter.

As the candy segments 42 are severed from the candy ribbon 41 responsive to the reciprocation of the knife blade 43, these fall in a trough 64 that is open at its forward inclined end 65 which terminates just short of the die receptacle that is positioned at the receiving station constituting a position in radial alignment with the trough 64. The segments 42 are displaced into the die receptacle by means of a disk 66 fixed to a rod 67 that is horizontally guided for reciprocal movement in upstanding brackets 68—69 comprising an integral part of the bracket 70 constituting the body of the forwardly extending trough 64. The bracket 70 is supported on confronting lugs 71—72 (Figures 4 and 14) formed integral with the tubular vertically shaped bearings 35—36. The bracket 70 is held securely in position by means of threaded elongated studs 73—73 which project downwardly through the bracket 70 for threaded engagement with correspondingly threaded apertures provided in confronting lugs 71—72.

The plunger rod 67 terminates in a furcated bracket 75 which is pivoted as at 76 to a link 77 having a furcated extremity 78. The furcated link extremity 78 is pivoted as at 79 to a down-

5

wardly inclined lever 80 that is pivotally supported as at 81 to a bracket 82. The bracket 82 is fixed to a cross member 83 that extends between the corner of the legs or standards 12 on the front side 18 of the frame 10.

The lever 80 has an actuating rod 84 pivoted as at 85 proximate to the lower extremity 86 thereof for connection to the power shaft, which will be described hereinafter, to operate the segment feeder 66 in timed relation with the cutting blade 43 and the other instrumentalities such as the die members which will be presently described.

In order to rotatably support the plurality of complementary die members for timed movement in conjunction with the candy feeding, severing, and displacing instrumentalities the frame top 11 has a depressed circular portion 87 (Figures 6 and 20) provided with an upstanding hub 88 having a vertical bearing 89 pressed into the axial bore 90 thereof to receive a vertical drive shaft 91 therethrough. A depressed circular portion 87 has an annular circular trough 92 defined by spaced circular walls 93—94 formed integral with the depressed frame top portion 87. The outer spaced wall 94 terminates in a horizontal surface 95 that has a depending peripheral flange 96 extending therefrom to define the outer limits of the depressed frame top portion 87.

A pair of confronting die supporting table mounts 97—98 are fixed to the drive shaft 91 for rotation therewith, there being complementary keys and key-ways 99—100 (Figure 6) provided therebetween so that rotation of the drive shaft 91 will insure the rotation of the confronting table mounts 97—98 that are maintained in spaced relation by a collar 101 (Figure 20). A ball bearing raceway 102 is interposed between the hub 88 of the depressed frame top 87, and the hub of the lower table mount 97 to insure smooth and high speed rotation of spaced table mounts 97—98 relative to the depressed frame top portion 87 and its hub 88.

A plurality of die receiving compartments 103—104 are circumferentially spaced in vertically designed relation in the table mounts 97—98 to receive a corresponding number of complementary die bodies 105—106, in this instance eleven in each of the table mounts 97—98. It should be observed that the die receiving compartments 103 in the lower table mount 97 communicates with the annular trough 92 formed in the depressed portion 87 of the frame top 11, and that the lower die bodies 105 are secured in the compartments 103 which are of complementary shape to serve as a support therefor. Similarly, the upper compartments 104 are provided with correspondingly shaped die bodies 106 that have overlapping slotted flanges 107—108 to afford the attachment thereof through the medium of threaded fasteners 109—110.

Confronting die elements 111—112 which may be of any suitable shape and type, are provided with shanks 113—114 which are reciprocally mounted within somewhat larger bores 115—116 provided axially through the die bodies 105—106. Compression springs 117—118 comprising continuous helical convolutions of wire, envelope the die shafts 113—114 below and above the die bodies 105—106, respectively, to normally urge the dies 111—112 to their inward extreme position relative to the die bodies 105—106. Suitable caps 119—120 are provided on the extremities of the die shafts 113—114 to serve as a stop for the springs 117—118 and also to ride over the cam surfaces 121—122 (Figures 17, 20 and 25).

6

The cam surfaces 121—122 comprise the actuators for the dies 111—112, respectively, and these are formed on cam bodies 123—124 serving as actuator tracks over which the die shank caps 119—120 ride over predetermined portions of their arc of travel. A plurality of stick receiving slots 125, in this instance one, is provided in the outer peripheral surface 125' of the lower table mount 97 along a radial median line of each die receptacle 103, to receive handle sticks 125" that extend inward to the center axis of the lower die element 111.

For instance, the cam track 123 (Figures 20 and 25) is fixed to the bottom of the annular trough 92 at approximately the circumferential position comprising substantially the sixth die position from the feeding trough 64 (viewed from Figure 5 and counting in a clockwise direction from the feeding position 64). At this position the cam track 123 would cause the lower die element 111 to be raised to its extreme upward position (Figure 20) to eject the previously formed candy 126 which is then rotated with the table mounts 97—98 to another position approximating the circumferential spacing of adjacent die elements 111—112 where an angular arm 127 is fixed to the frame top 11 as at 128 (Figure 5) so that the scraper 127 (Figure 23) will present an extended arm 129 between the die elements 111—112 to displace the completed candy unit 126 from the lowermost die 111.

The upper die element 112 which is complementary to the lower die element 111, is previously actuated to effect the downward depression thereof against the lower die element 111 by virtue of the passage of the upper die shank caps 125 against the cam surface 122 of the tract 124. The cam track is guided at both ends 130—131 (Figure 17) by upstanding threaded studs 132—133 which project from the cam track end bearing bosses 134—135 comprising part of the arcuate arm 136 (Figures 5 and 17).

The center of arm 136 is provided with a recess 137 to receive the head 137' of an adjusting screw 138. The head 137' is retained by a plate 138'. The screw 138 is carried on the end of supporting arm 139 and has a threaded end 140 for adjustment by means of handle 142 bearing on the base 141 at the center of 136. The arm 139 is then pivoted as at 143 to the furcated ears 144 comprising part of an upstanding webbed bracket 145 that terminates downwardly in a flange 146 to enable attachment to the frame top 11 by means of suitable fasteners such as machine bolts 147 (Figure 5).

With this arrangement, the radially extending bracket arm 139 can be readily pivoted to its extreme counter-clockwise inoperative position (viewed from Figure 15) so that the die elements 111—112 therebeneath are rendered accessible for cleaning, replacement or as operating conditions may require from time to time. Then, too, the degree of power exerted by the upper die element 112 relative to its lower die element 111, can be controlled to meet the requirements of different types of candies as well as compensate for wear.

The upper cam track 124 is positioned so that compression commences at the second die station from the feeding trough 64 and increases in degree to its extreme compression that is effected at substantially the fourth die station (viewed from Figure 5 and counting in a clockwise direction).

At substantially the fifth station from the feed-

ing trough 64, the upper die 112 is fully released and in the next adjacent station or substantially the sixth die position the lower cam track 123 begins to lift the lower die element 111 to accomplish the ejection of the completed candy 126 (Figures 20 and 24).

At the next adjacent position or substantially the seventh, the scraper arm 129 removes the completed candy 126 from the die receptacle 103. At this station an attendant may wrap, pack or otherwise process the completed candy 126 depending upon the dictates of commercial practice.

In order to automatically supply the handle sticks 125" to the lower die element 111 and to effect the support thereof at the desired elevation with respect to the concavity or shape of the complementary die elements 111-112, the stick slots 125 are provided to extend in the radially outer peripheral upraised surface 125' of the lower table die mount 97. The radial stick slots 125 connect with each of the die receptacles 103 provided in the lower table mount 97, and each of the lower die bodies 105 are provided with corresponding slots 148 (Figure 20) which align with the table mount slots 125' to receive the sticks 125" at approximately the same elevation as the top of the lower die element 111 when it is in its initial lowermost position in the die body 105.

With this arrangement, the candy segment 42 will be deformed by both complementary dies 111-112 into the shape of the latter around the inward extremity of the stick 125" responsive to the depression of the upper die element 112. Circumferential slots 149-150 in this instance too, are provided in the upraised peripheral surface 125' of the lower table mount 97 to minimize the weight of the table mount 97. To this end, the peripheral table mount extension 125' is of channel construction owing to the fact that the underside thereof is peripherally chambered as at 151 (Figure 13) similar construction to depressed frame top portion 87.

The sticks 125" are confined in the hopper 152 that has a conveying side wall extension 153-154 defining a restricted discharge opening 155 that communicates with the cylindrical bottom 156 formed thereon. The cylindrical hopper bottom 156 has an opening 157 along the length thereof which substantially conforms with and is somewhat larger than the sticks 125" (Figure 22). The stick distributor in the form of a cylindrical rotor 158 is journaled in the correspondingly shaped hopper bottom 156 for support on a shaft 159 that projects therefrom to impart rotation thereto.

The shaft 159 is fixed to the rotor 158, and is journaled in end bearings 160-161 provided on the end walls of the rotor bottom 156 so that the sticks 125" confined in the hopper 152 will be 60 distributed for individual deposit in the radial slots 125 of the lower die mount periphery 125'.

A plurality of longitudinally and extending stick receiving slots 162 are circumferentially spaced around the hopper rotor 158 (Figure 2) to individually discharge sticks through the elongated slot 157 in the cylindrical hopper bottom 156 so that sticks of different lengths may be individually discharged from the hopper 152, a partition 163 is adjustably mounted to the side vertical wall 164-165 of the hopper 152 so that the partition 163 can be moved toward and away from confronting hopper end walls 166-167.

To this end, the partition 163 is shaped to correspond with the cross-sectional shape of the 75

hopper 152, and it has angle brackets 168-169 confronting the side walls 164-165 to receive fastener bolts 170-171 therefor. The fastener bolts 170-171 travel in horizontal slits (not shown) which limit the extent of the slideable adjustment of the partition 163 and renders the hopper 152 operable for sticks of varying length within the range required therefor.

The hopper 152 is supported by a bracket 172 fixed to the frame top 11 by means of fasteners 173 (Figures 1 and 22). The bracket 172 has an upper arcuate extension 174 shaped to conform with the curvature and size of one side of the cylindrical hopper bottom 156 for attachment thereto by welding or other suitable attaching expedients. The hopper 152 is rigidly supported so that its bottom discharge slot 157 overlies and is in the path of the radial slots 125 provided in the die mount periphery 125' (Figure 22).

20 A stick supporting platform 175 is supported adjacent to the periphery 125' of the lower die mount 97 and it is supported by means of an angle 176 formed thereon for attachment on the frame top 11 with the same fastener 173 utilized for attaching the hopper supporting bracket 172 (Figure 22). A curved upstanding guide 177 cooperates with the stick supporting platform 175, to terminate in a bracket 178 which is radially slotted as at 179 to receive a fastener such as a bolt 180 which extends through the stick supporting platform 175 (Figures 21 and 22) so that the upstanding guide may be radially adjusted for sticks of any length handled by the hopper 152.

25 With this arrangement, the sticks 125" are deposited in the radial slots 125 and as the lower die mount 97 rotates, the stick is carried therewith against the stationary guide 177 which displaces it inwardly for the desired distance so that the inward stick extremity registers with the axis of the lower die element 111. The feeding of the sticks 125" is effected responsive to the rotation of the hopper rotor 158 in timed relation with the other operating instrumentalities as will appear 30 more fully hereinafter.

35 The instrumentalities thus far described are operated in timed relation from a common power source constituting an electric motor 181 fixed to the bottom frame plate 13 (Figures 1 and 7) for support thereon. The motor 181 carries a sprocket pinion 182 on the armature shaft thereof to impart rotation to a chain 183 that is in meshing engagement with a sprocket 184 (Figure 7) fixed to the driving shaft 185 of a speed reducer 186. The speed reducer 186 is also fixed to the bottom frame plate 13 so that the driven shaft 187 thereof imparts the desired speed of rotation to a sprocket wheel 188 that is in alignment with the sprocket wheel 189 fixed to a shaft 190.

40 The shaft 190 is journaled in the bearing brackets 191-192-193 that are attached through any suitable fasteners 194 to the bottom frame plate 13 to rotatably support the shaft 190 parallel to the driving chain 183. Another chain 195 is in meshing engagement with the sprocket wheels 188-189 so that rotation of the motor 181 will impart a reduced speed of rotation to the shaft 190. An eccentric cam 196 is fixed to the shaft 190 to oscillate a connecting rod 197 adjustably connected as at 198 to a lever 199 (Figure 8).

45 The lever 199 that is rotatably connected to a stub shaft 200 is journaled in alignment with bearing brackets 201-202 to rotatably support the stub shaft 200 in paralleled spaced relation with

the driven shaft 190. Suitable fasteners 203 anchor the bearing brackets 201—202 to the bottom frame 13. A ratchet wheel 204 is fixed to the stub shaft 200 to intermittently rotate therewith responsive to a pawl 205 that operatively engages the teeth of the ratchet wheel 204.

The pawl 205 is pivotally connected to the lever 199 as at 206 and a spring 207 normally urges the pawl 205 in a clockwise direction (viewed from Figure 8) to operatively engage the teeth of the ratchet wheel 204 so that the oscillation of the lever 199 responsive to the eccentric cam 196 will intermittently rotate the ratchet wheel 204 and its supporting shaft 200.

The stub shaft 200 carries a bevel gear 208 at one extremity thereto to mesh with the bevel gear 209 fixed to the vertical shaft 30, that supports the feed wheel 20. A spur gear 210 is fixed to the shaft 30 just beneath the frame top 11 (Figure 14) to mesh with another spur gear 211 fixed to the shaft 29 that carries the confronting feed wheel 19.

Consequently, intermittent opposite rotation is imparted to the confronting feed wheels 19—20 to displace the ribbon or strand of candy a predetermined distance. Thereupon, the knife 43 is caused to descend against the ribbon of candy, this being accomplished by reciprocal movement imparted to the rods 59—60 that terminate at their lower extremity in cam followers 212—213 which are operatively connected to eccentrics 214—215 fixed to the driven shaft 190.

The eccentrics 214—215 are rotatably positioned on the shaft 190 to pull the rods 59—60 downwardly after the feed wheels 19—20 have been momentarily rotated, thereby operating the knife 43 in timed relation with the feed wheels 19—20. This effects the severance of the strand 41 into segments 42 that are deposited on the trough 64 (Figure 6) and displaces them into the lower die 111 by means of the piston 66 that is intermittently actuated by the lever 80 with its connecting rod 84 (Figure 9) operatively connected to an eccentric 216. The eccentric 216 imparts reciprocation to the plunger rod 67 to displace the segments 42 into the lower die 111 just as soon as the knife 43 recedes upwardly from the path of the ribbon or strand 41.

Now, then, the driven shaft 187 of the speed reducer 186 is connected to a clutch 217 disposed beyond the sprocket wheel 188 to control the rotation of the bevel pinion 218. To this end, the rod 219 terminating in the handle 220 (Figure 7), which is accessible from the exterior of the frame 10 to operate the clutch 217 and control the rotation of the bevel pinion 218 that meshes with the bevel gear 221 fixed to shaft 91 proximate to the bottom from plate 13.

With this arrangement continuous rotation is imparted to the lower and upper die table mounts 97—98 to rotatably support the confronting die elements 111—112 and effect their reciprocal timed displacement by carrying the die shanks 113—114 with their end caps 119—120, respectively, in the path of the lower and upper cam tracks 121—122 to effect their actuation in the manner and timed relation above described.

In order to feed the sticks 125" in timed relation with the operation of the other instrumentalities, the driven shaft 190 (Figure 7) carries a sprocket wheel 222 at the extremity thereof which projects beyond the bearing 193 to mesh with a chain 223 extending upwardly to engage another sprocket 224 (Figure 1) fixed to the hopper rotor shaft 159 (Figure 21). It will be apparent, there-

fore, that the size of the sprockets 224 will determine the speed of rotation of the rotor 158 for controlled operation in the desired or required timed relation with the rotation of the lower and upper die table mounts 97—98.

5 The clutch control handle 220 can be utilized to render the die table mounts 97—98 stationary for any desired reason without de-energizing the electric motor 181.

10 While I have illustrated and described a preferred embodiment of this invention, it must be understood that the invention is capable of considerable variation and modification without departing from the spirit of the invention. I, therefore, do not wish to be limited to the precise details of construction set forth, but desire to avail myself of such variations and modifications as come within the scope of the appended claims.

I claim:

20 1. In a hard candy forming machine, the combination with a frame, of a table rotatively mounted on said frame, a plurality of uniformly spaced pairs of normally separated complemental die members on said table, means for rotating said table on said frame, means for effecting the displacement of continuous lengths of candy toward said table, means for severing said continuous length of candy into segments, means for displacing the candy segments between complemental die members as the table continuously rotates to bring complemental die members in the path of said table for moving one die member complement toward the other with the candy

25 segments therebetween for effecting the compression and cam shaping of said segments, and means for displacing the other die member complement for ejecting the segment from said die members.

30 2. In a hard candy forming machine, the combination with a frame, of a table rotatively mounted on said frame, a plurality of uniformly spaced pairs of normally separated complemental die members on said table, means for feeding non-edible sticks to said table with a portion thereof disposed between said complemental die members, means for rotating said table on said frame, means for effecting the displacement of continuous lengths of candy toward said table, means for severing said continuous length of candy into segments, means for displacing the candy segments between complemental die members as the table continuously rotates to bring complemental die members in the path of said table for moving one die member complement toward the other with the candy

35 segments therebetween for effecting the compression and cam shaping of said segments, and means for displacing the other die member complement for ejecting the segment from said die members.

40 3. In a hard candy forming machine, the combination with a frame, of a table rotatively mounted on said frame, a plurality of uniformly spaced pairs of normally separated complemental die members on said table, spring means for normally maintaining said complemental die members in spaced relation, means for feeding non-edible sticks to said table with a portion thereof

45 disposed between said complemental die members, means for rotating said table on said frame, means for effecting the displacement of continuous lengths of candy toward said table, means for severing said continuous length of candy into segments, means for displacing the candy seg-

ments between complemental die members as the table continuously rotates to bring complemental die members in the path of said displacing means, fixed cam means for moving one die member complement toward the other with the candy segments therebetween for effecting the compression and shaping of said segments around said sticks, and cam means for displacing the other die member complement in a corresponding direction for ejecting the segment from said die members.

4. In a hard candy forming machine, the combination with a frame, of a table rotatively mounted on said frame, a plurality of uniformly spaced pairs of normally separated complemental die members on said table, means for rotating said table on said frame, intermittent means for effecting the displacement of continuous lengths of candy toward said table, means for severing said continuous length of candy into segments, means for displacing the candy segments between complemental die members as the table continuously rotates to bring complemental die members in the path of said displacing means, fixed cam means for moving one die member complement toward the other with the candy segments therebetween for effecting the compression and shaping of said segments, and cam means for displacing the other die member complement for ejecting the segment from said die members.

5. In a hard candy forming machine, the combination with a frame, of a table rotatively mounted on said frame, a plurality of uniformly spaced pairs of normally separated complemental die members on said table, means for rotating said table on said frame, intermittent means for effecting the displacement of continuous lengths of candy toward said table, means for severing said continuous length of candy into segments, means for displacing the candy segments between complemental die members as the table continuously rotates to bring complemental die members in the path of said displacing means, fixed cam means for moving one die member complement toward the other with the candy segments therebetween for effecting the compression and shaping of said segments, cam means for displacing the other die member complement for ejecting the segment from said die members, and means in the path of the ejected segments for effecting the removal thereof from said table and die members.

6. In a hard candy forming machine, the combination with a frame, of a table rotatively mounted on said frame, a plurality of uniformly spaced pairs of normally separated complemental die members on said table, spring means for normally maintaining said complemental die members in spaced relation, means for rotating said table on said frame, intermittent means for effecting the displacement of continuous lengths of candy toward said table, means for severing said continuous length of candy into segments, cam means for displacing the candy segments between complemental die members as the table continuously rotates to bring complemental die members in the path of said displacing means, fixed cam means for moving one die member complement toward the other with the candy segments therebetween for effecting the compression and shaping of said segments, cam means for displacing the other die member complement in a corresponding direction for ejecting the segment from said die members, and means in the path

of the ejected segments for effecting the removal thereof from said table and die members.

5 7. In a device of the character described, the combination with a frame, of a table rotatably mounted on said frame, a plurality of complemental die members circumferentially spaced on said table, radial stick receiving slots in said table between the outer periphery and said die members, confronting candy feeding rollers on said frame for displacing a continuous ribbon of candy toward said table, reciprocally mounted severing means in the path of said feeding rollers for segmenting the continuous ribbon of candy, means for transferring the severed segments to said complemental die members as said table continuously rotates, and fixed cam means for operating said complemental die members to compress the segments around the sticks and effect the ejection thereof from said die members.

15 8. In a device of the character described, the combination with a frame, of a table rotatably mounted on said frame, a plurality of complemental die members circumferentially spaced on said table, radial stick receiving slots in said table between the outer periphery and said die members, hopper means for confining a supply of sticks above said table, means for successively transferring sticks from said hopper to said table slots with a portion thereof extending into said 25 complemental die members, confronting candy feeding rollers on said frame for displacing a continuous ribbon of candy toward said table, reciprocally mounted severing means in the path of said feeding rollers for segmenting the continuous ribbon of candy, means for transferring the severed segments to said complemental die members as said table continuously rotates, and fixed cam means for operating said complemental die members to compress the segments around the sticks and effect the ejection thereof from said die members.

30 9. In a device of the character described, the combination with a frame, of a table rotatably mounted on said frame, a plurality of complemental die members circumferentially spaced on said table, radial stick receiving slots in said table between the outer periphery and said die members, spring means for normally maintaining said complemental die members in confronting spaced relation, hopper means for confining a supply of sticks above said table, means for successively transferring sticks from said hopper to said table slots with a portion thereof extending into said complemental die members, confronting candy feeding rollers on said frame for displacing a continuous ribbon of candy toward said table, reciprocally mounted severing means in the path of said feeding rollers for segmenting the continuous ribbon of candy, means for transferring the severed segments to said complemental die members as said table continuously rotates, and fixed cam means for operating said complemental die members to compress the segments around the sticks and effect the ejection thereof from said die members.

35 10. In a device of the character described, the combination with a frame, of a table rotatably mounted on said frame, a plurality of complemental die members circumferentially spaced on said table, radial stick receiving slots in said table between the outer periphery and said die members, spring means for normally maintaining said complemental die members in confronting spaced relation, hopper means for confining a supply of sticks above said table, means for

successively transferring sticks from said hopper to said table slots with a portion thereof extending into said complemental die members, confronting candy feeding rollers on said frame for displacing a continuous ribbon of candy toward said table, reciprocally mounted severing means in the path of said feeding rollers for segmenting the continuous ribbon of candy, means for transferring the severed segments to said complemental die members as said table continuously rotates, and fixed cam means for operating said complemental die members to compress the segments around the sticks and effect the ejection thereof from said die members.

11. In a device of the character described, the combination with a frame, of a table rotatably mounted on said frame, a plurality of complemental die members circumferentially spaced on said table, radial stick receiving slots in said table between the outer periphery and said die members, spring means for normally maintaining said complemental die members in confronting spaced relation, hopper means for confining a supply of sticks above said table, means for successively transferring sticks from said hopper to said table slots with a portion thereof extending into said complemental die members, confronting candy feeding rollers on said frame for displacing a continuous ribbon of candy toward said table, reciprocally mounted severing means in the path of said feeding rollers for segmenting the continuous ribbon of candy, means for transferring the severed segments to said complemental die members as said table continuously rotates, and stationary cam means responsive to the rotation of said table for operating said complemental die members to compress the segments around the sticks and effect the ejection thereof from said die members.

12. In a device of the character described, the combination with a frame, of a table rotatably mounted on said frame, a plurality of complemental die members circumferentially spaced on said table, radial stick receiving slots in said table between the outer periphery and said die members, spring means for normally maintaining said complemental die members in confronting spaced relation, hopper means for confining a supply of sticks above said table, means for successively transferring sticks from said hopper to said table slots with a portion thereof extending into said complemental die members, confronting candy feeding rollers on said frame

for displacing a continuous ribbon of candy toward said table, means for intermittently rotating said feeding rollers, reciprocally mounted severing means in the path of said feeding rollers for segmenting the continuous ribbon of candy, means for transferring the severed segments to said complemental die members as said table continuously rotates, and stationary cam means responsive to the rotation of said table for operating said complemental die members to compress the segments around the sticks and effect the ejection thereof from said die members.

13. In a device of the character described, the combination with a frame, of a table rotatably mounted on said frame, a plurality of complemental die members circumferentially spaced on said table, radial stick receiving slots in said table between the outer periphery and said die members, spring means for normally maintaining said complemental die members in confronting spaced relation, hopper means for confining a supply of sticks above said table, means for successively transferring sticks from said hopper to said table slots with a portion thereof extending into said complemental die members, confronting candy feeding rollers on said frame for displacing a continuous ribbon of candy toward said table, reciprocally mounted severing means in the path of said feeding rollers for segmenting the continuous ribbon of candy, means for transferring the severed segments to said complemental die members as said table continuously rotates, and stationary cam means fixed to said frame above and below said complemental die members for operating said complemental die members against the urge of said spring means to compress the segments around the sticks and effect the ejection thereof from said die members.
